GUARD FOR WRINGER ROLLS

Arthur C. Davis, Canton, Ohio

Application June 12, 1934, Serial No. 730,207

4 Claims. (Cl. 68—32)

The invention relates to a guard for the rolls of a clothes wringer and more particularly to means for guarding the wringer rolls against articles passing therethrough from becoming entangled around the rolls.

In the use of the ordinary clothes wringer, it frequently happens that articles instead of passing properly through the wringer rolls will adhere to one roll or the other, often resulting in tearing of the article or even damage to the wringer rolls and making it necessary to reverse the movement of the rolls to untangle the articles therefrom.

The object of the present improvement is to provide a guard or stripper for each roll of a clothes wringer arranged to prevent articles from adhering to either roll, causing them to pass through the rolls in proper fashion.

It is known that attempts have been made to provide guards or strippers upon clothes wringers but such devices as have been attempted in the past do not allow for any variation in the size of the rolls, making it necessary to form and mount each guard to accommodate the particular roll on which it is to be used and not providing for any adjustment of the guard to compensate for wear upon the rolls.

A further object of the invention is to provide an adjustable guard for clothes wringer rolls adapted to compensate for variation in size or for wear upon the rolls.

A further object is to provide such a guard comprising a substantially flat member stationary relative to the bearings of the roll and a pair of curved stripper members adjustably mounted upon the flat member.

The above objects, together with others which will be apparent from an inspection of the drawing and the following description, or which may be later pointed out, may be attained by constructing the improved clothes wringer guard in the manner illustrated in the accompanying drawing, showing a preferred embodiment of the invention, in which

Figure 1 is a side elevation of a clothes wringer with the improved guard applied thereto;

Fig. 2, a transverse sectional view on an enlarged scale taken as on the line 2—2, Fig. 1;

Fig. 3, a detached perspective view of the guard for the upper roll; and

Fig. 4, a similar view of the guard for the lower roll.

Similar numerals refer to similar parts throughout the drawing.

55 The improved guard to which the invention per-

tains may be attached to a wringer of any usual and well known design which is provided with a frame including the channel upright end members 10 in which are mounted the upper and lower roll bearing blocks 11 and 12 respectively, the lower blocks being adapted to rest upon stops 13 in the lower portions of the uprights 10, and the upper blocks being engaged by the spring 14 carried in the top crossbar 15 and adjusted as by the screw 16.

The upper and lower rolls 17 and 18 respectively are mounted on the shafts 19 and 20 respectively, the ends of which project beyond the rolls and form journals, the upper journals being received in the elongated openings 21 in the bearing blocks 11 and the lower journals in the open slots 22 formed in the upper faces of the blocks 12.

The lower roll 18 may be positively driven in either direction in usual and ordinary manner as by gearing enclosed in the gear box 23. The usual drain table 24 may be provided at the lower end of the wringer frame and the shields 25 may be carried in the channel uprights 10 at opposite ends of the rolls.

All of the above parts may be of any usual and well known construction such as common in clothes wringers and the wringer in itself forms no part of the invention but is merely illustrated in order to show the application of the improved guard thereto.

Each of the roll guards is preferably formed of sheet metal or similar material and includes a central flat member and two curved guard or stripper members adjustably connected thereto and adapted to be positioned so that their edges are located on opposite sides of the roll near the center thereof and spaced just sufficiently from the surface of the roll to prevent contact therewith.

The guard for the lower roll 18 comprises the flat central strip of sheet metal 26, the ends of which may be slightly curved as at 27 to fit upon the shield flange 25. Spring clips 28 are fixed to the underside of the strip 26 at the end portions thereof to engage beneath the shield flanges 25 so as to position the lower guard and hold it against vertical movement.

The curved sheet metal guard or stripper members 29 are adjustably carried by the flat central member 26 as by the screws 30 located through slots 31 formed in the curved members 29. When the lower guard is positioned in the wringer, these curved guard or stripper members 29 are adjusted so that their free edges 32 will be spaced from

the periphery of the roll 18 only sufficiently to provide a clearance, being located on opposite sides of the roll at a point near the center thereof, as best shown in Fig. 2.

5 The upper guard comprises the flat central strip 33, the ends of which are adapted to rest upon the top of the upper bearing blocks 11, being held tightly thereon by the spring 14, as shown in Fig. 1. The curved guard or stripper members 10 34 are adjustably connected to the flat member 33 as by the screws 35 located through the slots 36 in the members 34. The edges 37 of these curved guard members 34 are positioned at opposite sides of the upper roll 17 near the center 15 thereof and spaced therefrom just sufficiently to prevent contact with the roll.

With this construction, as articles are passed 20 through the wringer in either direction, it will be seen that any article which has a tendency to 25 adhere to one roll or the other will be stripped from the roll by the curved guard members and caused to pass properly through the wringer instead of winding upon the roll, thus preventing tearing of the articles as well as damage to the rolls.

I claim:

1. In a wringer having a frame and a pair of 30 rotatable rolls journaled therein, guards for the rolls, each guard including a flat member mounted upon the frame, and a pair of curved members 35 adjustably connected to the flat member and terminating adjacent to opposite sides of the corresponding roll.

2. In a wringer having a frame including spaced 5 channel members, bearing blocks slideable in said channel members, rolls journaled in said bearing blocks, and a spring pressing upon the bearing blocks of one roll, a guard for each roll including a flat member and two curved members adjustably connected to the flat member and terminating adjacent to opposite sides of the roll, the ends of one flat member being located between said spring and the adjacent bearing blocks. 10

3. In a wringer having a frame including spaced 15 channel members, bearing blocks slideable in said channel members, rolls journaled in said bearing blocks, and shields upon said channel members, a guard for each roll including a flat member and two curved members adjustably connected to the flat member and terminating adjacent to opposite sides of the roll, and spring clips upon the ends of one flat member for attaching the same to said shields. 20

4. In a wringer having a frame including spaced 25 channel members, bearing blocks slideable in said channel members, rolls journaled in said bearing blocks, and a spring pressing upon the bearing blocks of one roll, and shields upon said channel members, a guard for each roll including a flat member and two curved members adjustably connected to the flat member and terminating adjacent to opposite sides of the roll, the ends of one flat member being located between said spring 30 and the adjacent bearing blocks, and spring clips 35 upon the ends of the other flat member for attaching the same to said shields. 25

ARTHUR C. DAVIS.
